UNITED STATES PATENT OFFICE.

JOHN F. COOLEY, OF ROCHESTER, NEW YORK, ASSIGNOR OF ONE-HALF
TO WILLIAM R. GRAY, OF SAME PLACE.

KITE.

SPECIFICATION forming part of Letters Patent No. 606,622, dated June 28, 1898.

Application filed September 4, 1897. Serial No. 650,670. (No model.)

To all whom it may concern:

Be it known that I, JOHN F. COOLEY, a citizen of the United States, and a resident of the city of Rochester, county of Monroe, and State 5 of New York, have invented certain new and useful Improvements in Kites, of which the following is a specification, reference being had to the accompanying drawings, in which—

Figure 1 is a perspective view of a kite embodying my invention. Fig. 2 is a front elevation, on a larger scale, of the same device. Figs. 3, 4, and 5 are views of details. Fig. 6 shows a modified form of a kite embodying my invention.

15 The object of my invention is to produce an easily-constructed, strong, and highly-efficient kite. I accomplish this object by the devices and arrangements thereof hereinafter set forth and claimed.

20 The kites produced before my invention herein described have been of two classes: first, the ordinary kite, including in this class the kite known as the "Malay," and, second, kites constructed upon what is now 25 known as the "principle of the aero plane." My present invention relates to kites of the latter class, involving certain radical improvements thereon.

In the drawings, A is the main spar of the 30 kite, which extends through the center thereof and connects the front and rear members. This spar may of course in large kites be trussed or otherwise stayed and strengthened in order to sustain the strains which it may

35 encounter. At each end of the main spar is attached (in the form shown in Fig. 1) a horizontal wing B and a smaller vertical wing C, the two wings B and C intersecting each other and being fastened to the main spar near its 40 end.

In the broader view of my invention I do not limit myself to the manner in which these wings and the spar are connected; but for the purpose of producing a strong, light, and at the same time efficient kite I prefer 45 to connect them in the following manner: Each of the wings is formed of a suitable air-resisting fabric, combining strength and lightness, stretched upon a framework having, in the case of the wing B, a front bar b and a rear bar b' . These bars being transversely fastened to the main spar sustain the fabric

in proper position for action. For the further purpose of cheap construction I make the bars b and b' of wire and unite them at the ends by the longitudinal bars b^2 . In fact, the whole 55 frame, consisting of the bars b , b' , and b^2 , is integral. The fabric B' of the horizontal wing B is not stretched tightly between the bars b and b' , but has some slack therein. The purpose of this slack is in order that in 60 winds of varying velocity the curvature of the surface of the fabric may change and adjust itself to the force of the wind. This principle is well known in connection with the sails of vessels, in which the sail is not 65 formed or strained to produce a flat surface, but is arranged with a due amount of slack, so that the angle of incidence and of reflection of the particles of air acting upon the surface may not cause an interference 70 nor counter-currents nor eddies of the wind, but may produce the effect, above mentioned, of self-adjustment with reference to the force of the wind and thus make the whole surface effective. At the middle of each of the wings 75 B' is a slot b^0 , extending directly across the wing from the front bar b to the rear bar b' . At the ends of this slot are curvatures b^{10} in the bars b and b' , which, when the same are formed of wire, may be produced by slightly 80 bending the wire; but if the bars are made of wood or of metal rods mere notches in these bars accomplish the same purpose as the curves b^{10} .

The vertical wing C has also front and rear 85 bars c and c' , which serve to strain the fabric C between them. This vertical sail is intended for two purposes: first, to keep the kite in proper position with reference to the wind, like the rudder or centerboard of a 90 vessel acting upon the water, and the fabric, therefore, of this wing is stretched tightly between the front and rear bars c and c' , and, second, to steady it for lateral or rotatory movements. These bars may be of wood or 95 metal or of any other suitable material; but I prefer for cheap construction to make a continuous frame of wire for this wing having front bars, as stated, and the end pieces c c^2 . In the main wing B the front and rear 100 bars are parallel, and in many constructions embodying my invention the bars c and c'

- may also be parallel. In the present instance said bars c and c' are bent at the middle to have inward curvatures c^{10} , which may engage in the curves b^{10} of the wing B' when the sail C is inserted through the slot b^0 in order that the two wings may properly intersect, and the bars c and c' slightly converge toward each other from the notches c^{10} toward each end of the wing in order that the end pieces c^2 may be small enough to pass through the slot b^0 and in order that the center portions of the bars c and c' may be sprung inward in order to permit the notches c^{10} to spring into the notches b^{10} .
- 15 The main spar, as shown in Fig. 5, is slit at each end to form the slots a and a' , which are made in intersecting planes at right angles to each other and extend from the end of the spar to a distance a little greater than the transverse width of the sails B and C .
- If now the sail C is inserted through the slot b^0 and the notches c^{10} engage in the notches b^{10} , the two sails intersect each other and may be set at right angles to each other, so that they may be intersected in the slots a and a' , whereupon by any suitable fastening, such as the ferrule A' , the extreme ends of the spar are held together, and the sails are locked and held in place. Any other fastening at the ends of the spar is obviously sufficient, such as winding with cord or wire. By releasing or removing the fastening at the ends of the spar the kite may be taken apart and packed flat for transportation.
- 30 The construction of the sails is the same at each end of the spar, and they are fastened to the bar in the same manner. When my device is used as a kite, it is best, however, that the rear system of sails shall be smaller than the forward system, as the function of the rear system is mainly to keep the front system in a proper position with relation to the wind for steadyng the kite against circular soaring, diving, or taking a position with too much sail-surface exposed to the wind, and thus diminishing its lifting power. As seen in Fig. 1, the kite-cord is fastened to the main spar at a point a^0 only a short distance back of the front system of sails, so that the leverage as between the two systems of sails upon the cord as a fulcrum is much in favor of the rear system, and for this reason also the rear system is and should be smaller than the forward system.
- 55 The sails or wings and spars may be guyed and braced in any suitable manner to produce strength and rigidity of the elements of the kite. The front bar b of the horizontal member of both the front and rear systems of sails is, however, bent, as shown in Figs. 1 and 2, in order to give a greater lifting power at the ends of the wings, and thus to produce a better balancing of the kite in the air and a better position of the fabric for obtaining a proper bearing against the wind. At a point a little more than one-half the distance from the main spar to the end of the front bar b a

guy is fastened, which extends from the spar to and over the upward extension of the bar c and to a similar point on the bar b on the other side of the main spar. The upper bar c^2 has a notch c^{20} in it, in which the guy may rest and be definitely held. This guy is made of such length as to bend or bow the bar b upward at its extremities in a uniform curve between the two points of fastening the guy and upon the main spar A as the middle of the curve. This curvature is clearly shown in Fig. 2 and, being even on both sides of the spar, produces the effects above mentioned. At the middle of the guy D , I prefer to introduce a yoke-like piece of metal d , engaging in the notch c^{20} , so that the guy cannot slip sidewise upon the upper bar c^2 .

In Fig. 6 is shown a construction having three main spars, three vertical wings, and one horizontal wing, which is adapted, by reason of its strength and the multiplying of the vertical sail members, to employ a greater length and width of horizontal wing for very high flights, the vertical wings tending to prevent side drift and to produce a straighter position with reference to the wind than a single vertical member only, because a very slight distortion of a single vertical member may have a considerable effect upon the position which the kite may take, which would be corrected when more than one member is used. The rear system of wings is, as described, a steering device in one respect.

This kite when magnified to proper proportions is adapted for use as an air-ship when provided with suitable propelling mechanism, and I do not intend in my broader claims, although I use the word "kite" in them, to limit my invention to the use of the device as a toy.

What I claim is—

1. The combination in a kite of a horizontal wing, having front and rear bars and slack air-resisting material between said bars and a smaller vertical guiding-wing intersecting said horizontal wing at right angles, and a steering device behind said wings.

2. The combination in a kite of two horizontal wings, each having front and rear bars and slack air-resisting material between said bars and a smaller vertical guiding-wing intersecting said horizontal wing at right angles, each system being connected to the other system by a longitudinal spar and the rear system having smaller wings than the other.

3. The combination in a kite of a horizontal wing, having the front edges bowed upwardly at the extremities and the rear edge straight, and the slack air-resisting material between said edges, and a smaller guiding-wing set in a plane intersecting the horizontal wing at right angles, and a steering device behind said wings.

4. The combination in a kite of two horizontal wings, each having the front edge bowed upwardly at the extremities and the rear edge straight, and each having slack air-resisting material between said edges, and a

vertical guiding-wing set in a plane intersecting each horizontal member at right angles, and each system being connected to the other by suitable means, as a longitudinal spar.

5. The combination of a main spar having two longitudinal slots in each end, at right angles to each other and horizontal and vertical wings set in said slots and intersecting

each other at right angles, and a fastening at the ends of the spar, and means for bowing to the front edges of the horizontal wings upwardly at the extremities.

JOHN F. COOLEY.
